UNITED STATES PATENT OFFICE.

ROGER W. OLMSTED, OF SAN FRANCISCO, CALIFORNIA, ASSIGNOR TO FOSTER & KLEISER COMPANY, OF SAN FRANCISCO, CALIFORNIA, A CORPORATION OF NEVADA.

POSTER-HANGER'S SCAFFOLD.

Application filed September 12, 1927. Serial No. 218,903.

This invention relates to scaffolding for poster hanger's use and has as its objects improved portable scaffolding especially adapted for quick erection and removal, which will be safe to work upon, and which will not mar the signs or posters, or their frames. Also such a rigging which will be light to carry about and cheap to manufacture.

- Briefly described my invention comprises
- 10 a plurality of vertically hanging poles or bars hooked over the upper edge of the sign-board, spaced outwardly therefrom and locked to the board at the bottom, also a ladder similarly suspended and locked, and a horizontal platform board carried at various heights by the suspended bars and the ladder.
  - 15 Fig. 2 is an enlarged broken side view of the ladder hooked and locked to the sign-board, and Fig. 3 is a front view of Fig. 2.
  - 20 Fig. 4 is an enlarged broken side view of one of the bars, and Fig. 5 is a front view of Fig. 4.
  - 25 Fig. 6 is a plan view of the ladder spreader and locking brace, and Fig. 7 is a plan view of the bar spreading and locking brace.

Before going into details of the scaffolding the sign-board structure should be considered, as its construction directly cooperates with the elements of the scaffolding in order to carry out the invention.

The sign-board best suited for application of my scaffolding consists of a sign panel 1 framed in a moulding 2 provided with a heavy outer edge or cap 3, usually of 2 x 6 timber, and the whole supported on vertical posts as at 4. Fig. 2 shows the sign-board itself in section embracing the above features.

Hooked over the upper edge of the sign-board near opposite ends are bars 5, and in the center of the sign-board similarly suspended is a ladder 6, the ladder and bars cooperating to support a plank or staging 7 for the poster hangers to stand upon in doing their work.

The ladder and bars are spaced outwardly from the bottom of the board by braces as shown respectively at 8 and 9.

In further detail the bars are preferably each a piece of angle iron to which a metal hook 5' is firmly secured, and the ladder is

made with sides converging at the upper end with a metal hook 6' secured thereto.

The brace or spreader 8 for the ladder consists of an angle iron arm 8 with a cross arm 10 at its forward end provided with downwardly extending flanges or fingers 11 adapted to straddle a rung of the ladder as indicated, while at the rearward end of the brace is a cross arm 12 provided with a hook or hooks as at 13 adapted to hook over the forward and upper edge of the lower moulding cap 3 (see Fig. 2), and the arm 8 is extended back beyond the cap 3 and formed with an upwardly turned end 14 to engage the rear side of the moulding cap. Thus the brace when in position shown in Fig. 2 is locked to the sign-board so that it can neither rise, fall, or be pulled or pushed out of engagement, except by first lifting the forward end from the rung 15 of the ladder to thereby drop the rear hook 14 from engagement with the rear of the moulding cap, thus permitting the brace to be pulled forwardly to free hook 13 from the moulding cap.

The braces 9 for the bars are also of angle iron and are each made with a cross arm 16 at their rear ends provided with hooks to engage the sign-board as described for the ladder brace. Braces 9 however extend forwardly beyond the bars so as to provide a support for the plank or staging 7 and the end 9' is bent upwardly to prevent the staging from being pushed off, whereas the brace 8 of the ladder supports the stage behind the ladder, as the ladder is spread further from the sign than the poles are.

Brace 9 is detachably supported on the bar by means of a bracket 17 on the bar which engages the outer side of the angle iron brace while a pair of stops 18 on the brace hold the bar in proper angular spread relation to the sign-board. To remove the brace it is first lifted from engagement with bracket 17 and then disengaged from the sign-board as described for brace 8. An additional bracket 17' is provided on the bracket to position the brace for signs of greater width, though it should be remarked that the sign frames are now almost all of standardized size so that adjustability of the brace to different positions is seldom required.

In use the staging is supported at either of two positions, at dotted position "A" across

the lower braces so that a workman thereon can work on the lower part of the sign, or at full line position "B" to enable the workman to reach the upper part of the sign.

5 In position B the staging rests on two upstanding brackets on the bars and a hanging bracket on the ladder. The upstanding brackets each comprise a strut 20 pivoted at its lower end to the bar 5 and at its upper 10 end to a support made of two pieces 21—22 pivoted respectively to the strut and the bar at opposite ends at 23—24 and to each other in the center at 25 so that the center joint may be broken by an upward push and the bracket 15 will fold against the bar to dotted position X. Section 21 of the support is here shown as an angle iron extending to the bar in overlying relation to section 22 so as to form a stop thereagainst when in open position.

20 The hanging bracket on the ladder comprises links 26 pivoted together at 27, and at the lower end at 28 to a horizontal supporting rod 29, while the forward ends of links and rod are pivotally connected to a block 30 positioned on the ladder and through which block several of the ladder rungs pass.

The ladder bracket as described may be folded upwardly against the ladder by first breaking the joint of the links.

30 For the staging any plank may be used, but I prefer a plank made of spaced strips as indicated.

In operation, the bars and ladder are hooked over the upper edge of the sign-board, the 35 braces locked to the lower edge; the brackets upfolded and the staging placed in either position A or B and the apparatus is ready for use. The ladder is best placed in the center between bars 5 so that workmen can quickly 40 reach either end of the sign, though it is of course possible to interchange it in position with one of the bars, or in short signs use but the ladder and one bar.

The cross arms on the braces locked to the 45 lower edge of the sign-board and to the ladder rung prevent any swinging of the scaffolding in use.

It should be noted that while the staging is used first at one level A or B and then at the 50 other to complete the sign, it is evident that for very large signs the apparatus might be greatly enlarged so that the staging could be placed in both positions at the same time, or

even more positions for the staging could be provided for.

In using the word "plank" in the claims hereto it is to be understood to cover any type of staging for the workmen to stand upon.

In contemplating the above disclosure it will be evident that many variations in detailed construction may be resorted to without affecting the mode of operation, and any such modifications as come within the spirit of the invention are intended to be covered in the appended claims.

I claim:

1. Portable scaffolding comprising a plurality of supporting members adapted to engage the upper edge of a sign-board structure and hang suspended therefrom, means spreading the members outwardly from the lower part of the sign-board, and means on said members arranged and adapted for supporting a plank in horizontal extension, said first mentioned means engaging the lower edge of the sign-board structure while preserving the entire scaffolding free from surface contact with the sign board.

2. The combination specified in claim 1 wherein one of said supporting members is a ladder.

3. The combination specified in claim 1 wherein one of said supporting members is a ladder and said plank passes in back of the ladder and in front of the other of said members when in position.

4. A portable scaffold unit comprising a bar provided with a hook at one end for hooking over the upper edge of a sign structure, and a brace at the lower portion adapted to hook to the lower edge of the sign structure for holding the bar spaced outwardly therefrom while preventing in or out movement of the bar.

5. Portable scaffolding comprising a plurality of rigid members hooked at the upper end and adapted for hooking over the upper edge of a sign-board structure so that the members will hang suspended in front of the sign-board, a brace at each member passing under and engaging the lower edge of the sign-board structure spacing the member outwardly therefrom and providing a support for a plank in horizontal extension along the face of the sign-board.

ROGER W. OLMSTED.
